ELECTRIC CONDENSER

Mendel Osnos, Berlin, Germany, assignor to Tele-funken Gesellschaft für Drahtlose Telegraphie m. b. H., Berlin, Germany, a corporation of Germany

Application May 5, 1932, Serial No. 609,401. Renewed July 25, 1936. In Germany July 2, 1931

3 Claims. (Cl. 175—41.5)

This invention relates to an improved electric condenser whose capacity varies very markedly with the temperature. A condenser of this invention is particularly adapted to use in a circuit for tuning the capacity of a vacuum tube transmitter, especially when short-waves are employed, and is to be controlled from a remote point or else for the purposes of stabilizing frequency of a valve transmitter controlled by the agency of a piezo-electric crystal.

According to the invention a condenser of this kind is created so that its active surface or its inter-electrode distance, or else both, are adjusted or regulated by a fluid possessing a large temperature coefficient of expansion or else by a gas (say, air) or a combination thereof. It is then feasible to heat the liquid or the gas or a combination of both, for example, by means of electric heating to a more or less high degree, with the result that the capacity of the condenser is regulable or adjustable at will at any desired rate.

A number of practical embodiments are shown in the drawing, of which,

Fig. 1 is a vertical cross section of the improved condenser having double walls;

Fig. 2 is a vertical cross section of a simple modification of this condenser;

Fig. 3 is a vertical cross section of another modification of this condenser;

Fig. 4 is a wiring diagram of the heating system.

Referring to Fig. 1, 1 and 1A denote a double-walled (jacketed) glass vessel of cylindrical form whose space between the lateral walls is very small (say, $\frac{1}{2}$ to 1 mm. in radial direction) but comparatively large between the bottom or end surfaces.

The space or cavity between the bottoms of the two cylinders is filled entirely by a suitable liquid 2 such as mercury, for instance. The space between the shells is not filled at all or only up to a certain height or level h ; but the entire space between the shells is suitably exhausted. The inner and the outer shell starting at a certain level h_0 is coated with a highly conducting metal 3, and 3A say, tinfoil.

The entire vessel is supported by a coil body 9, preferably made of metal which carries a winding 1 heated by current.

When the temperature of the liquid mercury increases its level will rise in the space between the lateral walls and there is formed a capacity between the liquid and the tinfoil coat.

It can be proved that the change in capacity of

such a condenser is directly proportional to the variation in the temperature, indeed, it is possible to write with close approximation:

$$C - C_0 = K \cdot V_0 (T - T_0) \quad (1)$$

where T_0 and C_0 the temperature and capacity, respectively when the level of the column of the liquid between the lateral walls is flush with the lower edges of the tinfoil coats or slightly above them, T a higher temperature and C a correspondingly increased capacity, V_0 the volume of the liquid at temperature T_0 , K a constant which is a function of the nature of the liquid and of the dimensions of the container.

If the liquid consists of mercury having a coefficient of thermal expansion of say 0.000181, if the distance between the surfaces of the shell=1 mm., the wall thickness 1 mm., and if a kind of glass is used having a dielectric constant=7, then with close approximation:

$$C - C_0 = 2.10^{-3} \cdot V_0 (T - T_0) \quad (2)$$

where C in cm., V_0 in cm. cu., and T in degr. C.

For short waves the capacitive reactance (capacitance) between the liquid and the metal plate 9 is very low so that the capacity according to Equation (2) comes to be close to that between the contacts 8 and 5.

Another simpler, though somewhat less favorable, embodiment is shown in Fig. 2, where 3 is a glass jar or bottle having a base or bottom considerably larger in area than the cross-section of the neck, and 21 a metallic electrode which can be screwed by means of a screwthread 4 on the collar ring or flange 22 so as to be at the correct distance above the liquid's level (mercury).

Now, if the liquid mercury is heated by means of the heater winding 7 wrapped around the body 9 the liquid will be caused to expand, the distance between its surface and the electrode 21 decreases, and the capacity increases.

Equation (2) shows, since the coefficient K is equal to 2×10^{-3} that a considerable volume V_0 must be provided in order that, in the presence of a moderate change in the temperature there may be obtained an appreciable change in the capacity. This involves the drawback that the condenser must be made of considerable size so that it would occupy much space in the metal housing of the transmitter. Another point is that a large volume of the conducting liquid confined inside the sheet-metal casing would occasion serious losses where short waves are dealt with.

Now, this drawback can be obviated by that

only part of the conducting liquid mercury is placed inside the sheet-metal housing, while the major part thereof is outside.

What follows further from Formula (2) is that

$$5 \quad V_0 = 0.5 \frac{C - C_0}{T - T_0} \cdot 10^8 \quad (3)$$

In practice it will be found advisable to make the quantity

$$10 \quad \frac{C - C_0}{T - T_0} = 1 \quad (4)$$

15 But it will be noted that V_0 even in the limiting case must be equal to 500 cu. cm. Assuming that the liquid is mercury, the weight thereof would be as much as $0.5 \times 13.6 = 6.8$ kilos. However, the volume of the conductive liquid may be appreciably reduced if for the actuation of the mobile electrode recourse is had to the thermal expansion of a liquid or gaseous substance which, while 20 being non-conducting or but slightly conductive, possesses a high coefficient of thermal expansion.

An embodiment of this kind is shown in Fig. 3. The constituent parts of the device are as follows:

23 31 is a space within the glass vessel 1 which is filled either with liquid or with a gas (air) or with both, which though not conducting electricity, possesses a high coefficient of thermal expansion; 2 is a conducting liquid mercury, 3 and $3a$ tinfoil coats, 1 the cylindrical glass vessel with a double wall being open inside a short distance above the bottom, 35 a cover being cemented on the glass vessel 1 , 9 a heater body, 37 insulated lead-ins to the heater body, 38 35 terminals for the latter, 39 a seal for the lead to the liquid electrode, 30 lead to the liquid electrode, 34 cementing of the cover 35 , 12 space above the conducting liquid between the shells of the two cylinders. The space is either 40 evacuated or contains a gas (air) of lower pressure than the pressure inside space 31 ; optionally also a heater coil 13 for heating the space 12 .

If the heater element 6 is heated electrically, the pressure inside space 31 will rise and thus 45 also the mercury in space 12 , and thus alter the capacity of the condenser.

If space 12 is small enough compared with space 31 it can be proved that the capacity of the condenser is nearly proportional to the temperature in the space 31 , if space 12 is evacuated. But if the space 12 is not exhausted then the 50 capacity of the condenser is proportional to the temperature and pressure difference between spaces 12 and 31 .

55 Instead of the space 31 it would be possible also to heat the space 12 , and then the capacity decreases with increasing heating current. It would also be feasible to heat both spaces though at different temperature, for it will be understood

that the change in capacity, as already pointed out, is predicated only upon the temperature differences of the two spaces.

The difference in the temperatures of the two spaces may be regulated, for instance, by means 5 of a bridge arrangement according to Fig. 4, where, as previously, 6 and 13 the heater resistors of the spaces 31 and 12 , while 14 denotes a potentiometer located at the control point whose voltage division is regulated by a slide contact 10 15 . In case of differential heating the resistances and the cooling conditions of spaces 31 and 12 may be so chosen that the temperature of the ambient will exercise no influence upon the capacity so that the capacity is merely a function 15 of the position of contact 14 (Fig. 4).

I claim:

1. An electric condenser comprising an insulating cylindrical casing having a double wall, said double wall having a relatively small internal 20 space in the radial direction but a substantially large space between the bottom of one of said walls and the top of the other wall, a metallic coating on the upper outside surface of each wall, a mobile electrode within said walls, and an 25 external electric heating element comprising a disk-like coil body having a heater winding and located below said container to control the level of said mobile electrode.

2. An electric condenser comprising an insulating cylindrical casing having a double wall, said double wall having a relatively small internal space in the radial direction but a substantially large space between the bottom of one of said walls and the top of the other wall, a metallic 35 coating on the upper outside surface of each wall, a mobile electrode located within the lower portion of said walls, the space in the upper portion of said walls being evacuated, and an external electric heating element comprising a 40 disk-like body having a heater winding and located below said container to control the level of said mobile electrode.

3. An electric condenser comprising an insulating cylindrical casing having a double wall, 45 said double wall having a relatively small internal space in the radial direction but a substantially large space between the bottom of one of said walls and the top of the other wall, a metallic coating on the upper outside surface of each wall, a mobile electrode of mercury within the lower portion of said walls, the space in the upper portion of said walls being evacuated, and an external electric heating element comprising a disk-like body having a heater winding and located below said container to control the level of said mobile electrode.

MENDEL OSNOS.
